UNITED STATES PATENT OFFICE.

CHARLES D. GERVIN, OF NEW YORK, N. Y.

DESIGN FOR A GAS-BURNER.

SPECIFICATION forming part of Design No. 30,619, dated April 25, 1899.

Application filed April 21, 1897. Serial No. 633,191. Term of patent 7 years.

To all whom it may concern:

Be it known that I, CHARLES D. GERVIN, a citizen of the United States, and a resident of the city of New York, in the county and State 5 of New York, have invented and produced a new and original Design for a Gas-Burner, of which the following is a specification, reference being had to the accompanying drawings, forming a part thereof, and in which—

10 Figure 1 is a perspective view of the said burner as seen from above, and Fig. 2 is a perspective view thereof as seen from below.

The nature of my novel design consists in a gas-burner formed in the following manner: 15 The central body of the burner is of inverted-acorn shape with vertical beads converging downward to its contracted lower end. Beneath this is a cylindrical base uniting with the body by a molding and encircled at its 20 lower end by a bead and having in its bottom an annular range of perforations. Above the body is a gallery projecting outward and

downward, having a dished upper surface, in which are radial slots harmonizing with the vertical beads in the body. The gallery is 25 surmounted by a dome of nearly cylindrical shape, converging slightly upward and having a slightly-convex top, in which are several concentric ranges of perforations. The “dished” form or vertical curvature of the 30 gallery, as represented in Fig. 1, causes it to project upward toward the center and assume a nearly vertical position, where it merges with the nearly vertical walls of the “dome.”

The following is what I claim as new and 35 of my invention in the above-described ornamental design for a gas-burner:

The design for a gas-burner; substantially as herein shown and described.

CHARLES D. GERVIN.
